[57] **CLAIM**

The ornamental design for a foldable seat cushion with carrying strap which may be microwaved to provide warmth, as shown and described.

DESCRIPTION

FIG. 1 is a top plan view of a foldable cushion embodying my design with the attaching strap placed on top; FIG. 2 is a front elevational view of the cushion as shown in FIG. 1 with the attaching strap on top, the rear view being a mirror image thereof; FIG. 3 is a bottom plan view of the cushion as seen in FIG. 1;

FIG. 4 is a left side elevational view of the cushion as shown in FIG. 1;

FIG. 5 is an enlarged perspective view of the cushion folded for carrying purposes; and,

FIG. 6 is a right side elevational view thereof.

The fabric pattern fragmentarily shown in FIGS. 1-6, is understood to extend throughout the surface of the claimed design.
